J. J. GROSHANS, OF BUFFALO, NEW YORK.

Letters Patent No. 70,833, dated November 12, 1867.

IMPROVED DRYING-ATTACHMENT FOR PAPER-RULING MACHINES.

The Schedule referred to in these Letters Patent and making part of the same.

TO ALL WHOM IT MAY CONCERN:

Be it known that I, J. J. GROSHANS, of Buffalo, in the county of Erie, and State of New York, have invented a new and improved Drying-Attachment for Paper-Ruling Machines; and that the following description, taken in connection with the accompanying drawing, hereinafter referred to, forms a full and exact specification of the same, wherein I have set forth the nature and principles of my said improvements, by which my invention may be distinguished from all others of a similar class, together with such parts as I claim, and desire to have secured to me by Letters Patent.

This invention consists in applying to paper-ruling machines a revolving fan, in such a manner that the ink on the freshly-ruled paper will be rapidly dried, and the paper, under the influence of the blast generated by the revolving fan, be made to drop evenly into the box or receptacle prepared to receive it.

The accompanying drawing represents a perspective view of my invention.

A represents the shaft of the fan, which is constructed of hard wood, and square, or nearly so, in its transverse section, and sufficiently long to extend across the machine. This shaft has two brass or steel springs B attached to it, one near each end, by pivots a. The outer ends of these springs are perforated each with a hole, b, to fit over pins c in the shaft A; and C is a pasteboard or tar-board fan, about nine inches wide, with small wings d about one and a half inch wide, one at each end. This fan is fitted on the pins c, the latter passing through perforations in the fan, and the springs B hold the fan firmly against the shaft. Whenever it becomes necessary to renew a fan, the springs B are raised free from the pins c and turned around, and fan detached and another inserted on the pins, and the springs turned back and adjusted on the pins. The shaft of the fan is placed on the lower beams of a paper-ruling machine, and in such a relative position with the ruled paper that the rotation of the fan, which may be given it from any suitable working part of the machine, will generate a blast to dry the ink, and also cause the paper to be discharged evenly into the box prepared to receive it.

Having thus described my invention, I claim as new, and desire to secure by Letters Patent—

1. The application of a revolving fan to paper-ruling machines for the purpose of drying the paper, and causing the same to be discharged smoothly into the box prepared to receive it, substantially as set forth.

2. The manner of constructing the fan, substantially as shown and described, to wit, having the fan composed of pasteboard, tar-board, or an equivalent material fitted on pins c in the shaft, and retained in position by springs B, substantially as shown and described.

J. J. GROSHANS.
